FUNGICIDAL LIQUID CONCENTRATE WITH
PROPYLENE GLYCOL

William J. Entley, Charleston, and Harry A. Stansbury, Jr., South Charleston, W. Va., assignors to Union Carbide Corporation, a corporation of New York
No Drawing. Filed Nov. 26, 1965, Ser. No. 510,101
3 Claims. (Cl. 167—42)

This invention relates to a liquid concentrate formulation for fungicidal mixtures.

U.S. Patent 3,166,469 to Pass et al. discloses the advantages of applying fungicidal compositions containing two previously known fungicides in combination, viz. 2-heptadecylglyoxalidine which is sold by Union Carbide Corporation under the common name "Glyodin" and n-dodecylguanidine acetate, sold by American Cyanamid Company under the trademark "Cyprex" and commonly known as "Dodine." The terms "Glyodin" and "Dodine" as used hereinafter are intended to refer to the commercially pure chemicals which are the fungicidally active components in formulations containing them.

The utility of this fungicidal mixture has, however, been limited by the solubility characteristics of the two components which are such as to have heretofore precluded development of a stable liquid formulation concentrate. Such a concentrate is convenient to use and thus preferred by orchardists. "Glyodin" is a waxy solid with a melting point of 62° C. to 68° C. and is thus not readily formulated as a wettable powder. Commercially, it is sold in an isopropanol solution containing 30 percent by weight of 2-heptadecylglyoxalidine in the form of its acetate salt. "Dodine" is normally available as a wettable powder formulation containing 65 percent by weight of n-dodecylguanidine acetate, the remainder being an inert particulate solid carrier, e.g., bentonite, and about 5 percent of a surfactant.

The two known aqueous formulations for the fungicidal mixture are described in the Pass et al. patent in Examples 1 and 2. One is a liquid mix in which a 30 percent solution of "Glyodin" in isopropanol and "Dodine" as a 65 percent wettable powder are charged into a tank full of water and the resulting mixture is continuously agitated to keep the components in suspension. In the other formulation a dry product is applied as a spray by suspending the dry powder in a large volume of water and maintaining vigorous agitation.

The difficulty with these known formulations is that they require handling of a dust material by the applicator which involves mixing problems, contamination of persons and facilities, and waste of some material. In addition, the tank water needs to be continuously agitated to maintain suspension of the dust.

The present invention provides a liquid concentrate in which the technical "Glyodin" and "Dodine" have been mixed in proportions optimum for fungicidal effectiveness. The invention utilizes the technically pure active fungicidal ingredients and thus obviates prior formulation of the "Glyodin" in isopropanol and of the "Dodine" as a wettable powder as required by the prior art techniques. Being a liquid concentrate, the present formulation is easy to handle and obviates all the problems of working with a dust described above. In addition, the liquid concentrate of this invention forms a solution when added to water so that the actual spray need not be kept under constant agitation.

Essentially, the present invention comprises liquid concentrate formulations containing "Glyodin" and "Dodine" characterized by the presence of propylene glycol. It has been found that when certain percentages of propylene

2

glycol are added to the two-component fungicidal mixture, a stable liquid concentrate formulation is obtained which exhibits excellent sprayability when mixed with water. In this respect the use of propylene glycol has been found critical inasmuch as the use of other common solvents did not result in usable formulations but rather led to formation of turbid suspensions not suited for mixing or spraying.

The compositions of this invention may contain the two active fungicidal components in a proportion of from about 0.8 part by weight to about 15 parts by weight of "Glyodin" per part by weight of "Dodine." However, in preferred combinations, from 1 to about 8 parts of "Glyodin" are provided for every part of "Dodine" and the optimum ratio is about 4 parts of "Glyodin" for every part of "Dodine." Use of this ratio appears to result in most effective disease control. The compositions are further characterized in that they contain from about 10 to about 30 parts by weight of propylene glycol per part by weight of "Dodine." It has been found that at least 10 parts by weight of propylene glycol per part of "Dodine" are required to give readily water-dilutable concentrates. Use of more than 30 parts of propylene glycol results in low toxicant concentration in the concentrate and gives no advantages in stability or sprayability of the diluted concentrate. In addition, the compositions may contain a certain amount of isopropanol or other solvent in which the technical "Glyodin" material may be commercially available. The liquid concentrate formulations of this invention thus contain from about 10 to about 40 percent by weight of 2-heptadecylglyoxalidine, from about 3 to about 10 percent by weight of n-dodecylguanidine acetate, and from about 50 to about 87 percent by weight of propylene glycol, provided that at least 10 parts by weight of propylene glycol are provided for every part by weight of n-dodecylguanidine acetate.

The liquid concentrates are prepared by physically admixing the components in the above-indicated ratios to result in a clear solution. If the concentrates are used at very low temperatures (ca 0° C.) slight warming may be necessary to maintain a clear, readily dilutable concentrate. If one of the fungicidal components is available in solution, e.g., "Glyodin" in isopropanol, such a solution may be admixed with the other components of the concentrate and the isopropanol optionally evaporated by distillation under reduced pressure.

To demonstrate the criticality of using propylene glycol comparative tests were carried out using the following materials in place of propylene glycol: ethylene glycol, isopropanol, butyl Cellosolve, dimethylformamide, dimethylsulfoxide, Carbitol acetate, Cellosolve acetate, ethylene glycol diacetate, 1,3-butanediol, glycerol.

Use of each of the above materials in the amounts indicated for propylene glycol results in a cloudy, turbid suspension unsuitable for agricultural application.

To determine the effectiveness of the formulation of this invention in agricultural applications, the formulation of this invention was applied to combat bean mildew, bean rust, tomato early blight and cucumber anthracnose in side-by-side tests with the conventional formulations described above, according to the following procedure.

Bean, tomato, and cucumber plants were sprayed on a revolving turntable with the indicated formulation for 30 seconds to apply about 100 milliliters of formulation. The treated plants were then stored at room temperature for a period of 24 hours. After the storage period, one half of the plants were sprayed on the turntable with 200 milliliters of water (indicated as rain treatment) and then dried. The remaining half received no additional treatment. Then all of the test plants were infested with the indicated fungus by brushing their leaves lightly with

infested plants from a stock culture, or by spraying them with a stock spore suspension. The plants were held for seven to ten days at conditions optimum for fungal growth. The degree of protection on primary leaves was visually rated according to the following designations:

- (1)=no activity
- (2)=little control
- (3)=about 50% effective
- (4)=excellent control
- (5)=complete control

The results are set forth in Table I, below. Concentrations of the active toxicants in the applied formulation are given in parts per million for each toxicant.

4
are provided for every part by weight of n-dodecylguanidine acetate.

5 2. A fungicidal concentrate as claimed in claim 1 comprising from about 10 to about 40 percent by weight of 2-heptadecylglyoxalidine, about 1 part by weight of n-dodecylguanidine acetate for every 4 parts of 2-heptadecylglyoxalidine, and about 10 parts by weight of propylene glycol for every part of n-dodecylguanidine acetate.

10 3. A fungicidal concentrate as claimed in claim 2 comprising from about 25 to about 28 percent by weight of 2-heptadecylglyoxalidine, from about 6 to about 8 percent by weight of n-dodecylguanidine acetate, and about 65 percent by weight of propylene glycol.

TABLE I.—FUNGICIDAL TEST RESULTS FOR COMBINATIONS OF GLYODIN AND DODINE IN DIFFERENT FORMULATIONS

Formulation	Concentration of active toxicant in water (p.p.m.)	Ratings								Counts ¹

“Glyodin” (technical) plus “Dodine” (technical) in propylene glycol ⁵	1,035+250 259+60 65+15	(4) 4 3	(4) 4 3	(4) 4 4	(4) 4 3	5 5 4	5 5 4	5 5 4	5 5 4	34 39 48	36 59 43
Control		1	1	1	1	1	1	1	1	136	169

¹ Number of lesions per 4 leaves.

² Water (200 ml.) sprayed on plants 24 hours after treatment.

³ Dissolved in ethyl alcohol before addition of water. The final formulations at 250 p.p.m. contained 10 percent alcohol by volume.

⁴ The sprayed plants showed a phytotoxic response.

⁵ The concentrate contained 65 percent by weight of propylene glycol in each instance.

It can be seen that the liquid formulation of this invention possesses the advantages of a liquid formulation with undiminished fungicidal effectiveness.

What is claimed is:

1. A fungicidal liquid concentrate formulation comprising from about 10 to about 40 percent by weight of 2-heptadecylglyoxalidine, from about 3 to about 10 percent by weight of n-dodecylguanidine acetate, and from about 50 to about 87 percent by weight of propylene glycol, provided that at least 10 parts by weight of propylene glycol,
